THOMAS WALKER, OF TROY, NEW YORK, ASSIGNOR TO EDWARD J. HICKS
AND GURDON G. WOLFE, OF SAME PLACE.

Design No. 2,991, dated March 31, 1868.

DESIGN FOR A STOVE-DOOR.

The Schedule referred to in these Letters Patent and making part of the same.

TO ALL WHOM IT MAY CONCERN:

Be it known that I, THOMAS WALKER, of the city of Troy, in the county of Rensselaer, and State of New York, have invented or produced a new and original Design for Stove-Plates, of which the following is a full and exact description, reference being had to the accompanying photograph of a stove-door having my said design.

This design consists essentially of the compound ornament, A, arranged on a panel, B, having ornamented corners, C, all shaped and disposed upon a stove-plate so as to present the appearance represented in the aforesaid photograph.

What I claim as my invention or production, and desire to secure by Letters Patent, is—

The design for stove-plates herein set forth and shown.

In testimony whereof, I hereunto set my hand, this 11th day of February, 1868.

THOMAS WALKER.
